UNITED STATES PATENT OFFICE.

GEORGE HAVELL, OF NEWARK, NEW JERSEY, ASSIGNOR TO THE HAVELL MANUFACTURING COMPANY, OF SAME PLACE.

DESIGN FOR A BICYCLE-LAMP.

SPECIFICATION forming part of Design No. 30,449, dated March 28, 1899.

Application filed February 24, 1899. Serial No. 706,748. Term of patent 7 years.

To all whom it may concern:

Be it known that I, GEORGE HAVELL, a citizen of the United States, and a resident of Newark, in the county of Essex and State of New Jersey, have invented and produced a new and original Design for Bicycle-Lamps, of which the following is a specification, reference being had to the accompanying drawing, forming part thereof.

10 My design is shown in side elevation in the accompanying drawing. As will be seen, it comprises a lamp-body of hour-glass shape, the adjoining sections 1 and 2 of which are substantially parabolic in cross-section and connected by a reduced neck, across which 15 extends a support 3 for a reflector 4, parabolic in cross-section, which latter terminates in an outwardly-spreading convex flange 5. Rising centrally from the upper part of the 20 reflector is a cylindrical chimney 6, surmounted by a dome-shaped cap 7. The upper part of the lamp-body terminates in a spherical dome 8, terminating in a cylindrical boss 9,

which supports an adjusting-screw 10. The bottom of the lamp-body terminates in a cup 11, having a bulging or convex face and somewhat less in diameter than the milled edge 12 of the lower parabolic section of the body. A cylindrical tube 13 connects the lower parabolic portion of the lamp-body with the reflector 4, and about midway on the latter is a circular cup or socket 14 for a colored side-light lens, as shown.

Having thus described my invention, what I claim as new, and desire to secure by Letters Patent, is—

The design for a bicycle-lamp as herein shown and described.

In testimony whereof I have hereunto subscribed my name this 15th day of February, 40 A. D. 1899.

GEORGE HAVELL.
